GEORGE W. SWIFT, JR., OF BORDENTOWN, NEW JERSEY, ASSIGNOR TO GEORGE W. SWIFT JR., INC., OF BORDENTOWN, NEW JERSEY, A CORPORATION OF NEW JERSEY

MACHINE AND PROCESS FOR MAKING CORRUGATED BOARD

Application filed July 23, 1931. Serial No. 552,630.

This invention relates to machines for making corrugated paper board and more especially to that type of said machines in which a pair of intermeshing paper-corrugating rolls operate upon a web for corrugating it, after which said corrugated web while it remains in one of the corrugating rolls, has its tips provided with adhesive preparatory to applying a liner web thereto under the pressure roll between which and the corrugating roll, the corrugated web and liner are passed. For this purpose, the corrugating rolls and pressure roll are usually mounted on rotary axes arranged in a common vertical plane while an adhesive fountain roll is usually arranged to apply adhesive to the tips of the corrugated web as it moves downwardly around the lower corrugated roll on its way to have the liner web applied thereto under the pressure of said pressure roll.

Up until ten to fifteen years ago, it was not uncommon to operate machines for making corrugated boards at a linear speed of from 25 60 to 70 feet per minute. At the present time, machines of this character may be operated at a speed running as high as 300 linear feet per minute. The feeding mechanism of machines of this nature usually consists of a plain drum which is pressed against and rotated by the lower corrugating roll. While this device is sufficient for applying a liner sheet to a corrugated web at a low velocity of movement, it is not suitable for high velocities. Thus, due to the inter-tooth spaces of the corrugating roll, the feeding action between it and a plain pressure roll, is non-uniform. For example, in an 8" corrugating roll operating tightly against the peripheral 40 surface of a plain drum or pressure roll, the circular pitch of the flutes in the former may be in the neighborhood of three-tenths of an inch. By actual measurement, this may produce a variation of about .0001 inch in the effective radius of the corrugated roll so that the linear feed of the paper varies considerably. As the speed of the machine is increased, the effects of this variation as well as of the tension on the paper web, accompanied 45 by an increased vibration of the several parts, produces an increasing tendency of the paper to pull back. In consequence, the flutes of the corrugated web are apt to be deformed so that after one liner sheet has been applied to the corrugated web, said flutes will vary materially in depth. As a result, when a second liner sheet is applied to the other face of the corrugated web, the relatively higher flutes in the corrugated web will operate to hold said second liner sheet away from the lower flutes and thus produces an inferior product.

The primary object of this invention is to provide an improved process and means of improved construction for producing high-grade corrugated board at high linear velocity. Toward the attainment of this purpose, my present invention contemplates the provision of one or more additional feed rolls or drums for cooperating one at a time with one of the corrugating rolls for the purpose of providing a more uniform and a better sustained feeding action while at the same time prolonging the period of drying under a sustained pressure produced by this feeding action. As an illustrative embodiment of my invention, I have shown on the drawings two plain pressure rolls or drums which operate against a corrugated roll in divergent planes through the rotary axis of the latter, the arrangement being such that the maximum effect between one of the drums and the crown of a tooth of the corrugating roll becomes active in alternate relation to that occurring between the other pressure drum and a tooth of the corrugating roller. By means of this construction, an extra squeeze or impingement is applied to the joined webs and inasmuch as the pressure rolls are spaced around the periphery of the corrugated roll and operate thereon in alternation, it becomes possible to secure a practically continuous feed of the corrugated board at a high velocity, such, for example, as a linear velocity of 300 feet per minute. In effect, with two pressure rolls, the space between the teeth is practically cut in halves, the result being that any tendency of a hold back is prevented. Hence, corrugations of uniform depth are produced and the feeding action is made practically 100

uniform, so that when the second liner sheet is applied, the product will be of uniform quality. Furthermore, as the double-faced corrugated board is fed to the cutters for cutting them to predetermined lengths, there is no appreciable slippage in the rolls since the belts are enabled to draw the corrugated board up to the cutters under a substantially continuous and uniform feed.

10 In the drawings which show a preferred embodiment of my invention,

15 Figure 1 is a vertical diagrammatic view showing the essential elements of a paper board manufacturing machine constructed in accordance with the underlying principle of this invention;

20 Figure 2 is an enlarged fragmentary side elevation of the same.

25 Referring more particularly to the drawings, a web 1 which passes about a guide roller 2 moves downwardly and is passed between an upper corrugating roll 3 and a lower corrugating roll 4. The corrugated web as it passes downwardly around the corrugating roll 4, has its tips brought into contact with a silicate-applying roll 5 operating in a bath of silicate 6 within a container 7. Following this application of adhesive, the corrugated web passes downwardly and to the right between the corrugating roll 4 and a pressure roll or drum 8 which presses a liner web 9 against the silicated tips of the corrugated web. Said liner web is drawn from a mill roll (not shown) and passes upwardly around a guide roller 10 and thence between the pressure roll 8 and the corrugated web. The corrugated web with the liner sheet attached is then caused to follow around the periphery of the lower corrugating roll 4 and between said lower corrugating roll and a second pressure roll 11 which applies an additional squeeze to the joined webs in alternation with that imparted by pressure roll 8, the relative angular disposition of said pressure rolls 45 around the axis of corrugating roll 4 being quantitatively measured by a mixed fractional multiple of the circular pitch of the teeth on the corrugating roll 4. It will thus be understood that as the squeezing pressure between the lower corrugating roll 4 and pressure roll 8 eases up on one portion of the single-faced corrugated board, the squeezing pressure between the pressure roll 11 and said corrugating roll 4 is increasing on another portion thereof, and vice versa. This construction and arrangement of parts has been found to produce a uniform speed to the single-faced corrugated board and to maintain the united webs under uniform pressure as it passes around the corrugated roll from one pressure roll to the other in such a way as to prevent the deformation of the corrugations of the corrugated web due to hold-back of the mill rolls. Thus, if there is but a single pressure roll, and the united webs are drawn

tangentially from the cooperating rolls as indicated in dotted lines in Figure 2, whenever the pressure roll comes opposite to an inter-tooth space, there is a tendency for slippage due to a materially lessened pressure so that under high velocities the hold-back of the mill rolls causes the flutes in the corrugated web to be pulled out of shape and dimension so that when the second liner web is applied thereto, an effective bond cannot be formed between the second liner web and all of the tips of the corrugated web. In the preferred embodiment of my invention shown on the drawings, I prefer to pass the corrugated web with one liner around the spaced pressure rolls 11 and 8 in its movement toward the mechanism (not shown) for applying the second liner web.

I claim:—

1. In a corrugated paperboard machine, the combination of corrugating rolls cooperating with each other in the common plane of their rotary axes, pressure rolls peripherally contacting with one of said paper-corrugating rolls in angularly displaced planes including the rotary axis of that paper-corrugating roll, the relative angular displacement of said planes being measured by the circular pitch of the paper-corrugating roll multiplied by a mixed fraction.

2. In a corrugated paper board machine, the combination of upper and lower paper-corrugating rolls having their rotary axes arranged in a common plane, a pressure roll peripherally contacting with the lower corrugating roll in said common plane, a second pressure roll peripherally contacting with the lower corrugating roll in a plane angularly displaced with respect to the first-mentioned plane, the periodic contacts between the teeth of said lower corrugating roll and one pressure roll being alternately timed with respect to the periodic contacts between the lower corrugating roll and the other pressure roll.

3. In a corrugated paper board machine, the combination of two paper-corrugating rolls cooperating in a common plane including their rotary axes, pressure rolls peripherally contacting with one of said corrugating rolls in angularly-displaced planes through the rotary axis of that paper-corrugating roll, the relative angular displacement of the last-mentioned planes being such that at the instant one cuts one of the teeth of the pressure roll, the other cuts a space between two successive teeth.

4. In a machine for making corrugated paper board, the combination of a pair of intermeshing paper-corrugating rolls having their rotary axes arranged in a common vertical plane, of a pressure roll operating on the lower paper-corrugating roll in said common plane, and a second pressure roll operating on said lower paper-corrugating roll in a

plane including the axis of said lower paper-corrugating roll and angularly displaced from the first-mentioned plane of centers, the relative angular disposition of said planes being such that when one of said planes includes the central radial line of a tooth of said lower paper-corrugating roll, the other intersects a space between two successive teeth of said lower paper-corrugating roll.

10. 5. In a machine for making corrugated paper board, the combination of a pair of intermeshing paper corrugating rolls having their rotary axes arranged in a common vertical plane, of a pressure roll operating on the lower corrugating roll, said pressure roll being journaled upon an axis in said plane of centers of said corrugating rolls, means for feeding a web to said corrugating rolls and around the lower corrugating roll, means 15 for feeding a liner web between said pressure roll and the corrugated web on the lower corrugating roll, and a second pressure roll operating on the corrugated web on said lower corrugating roll in alternation with the first-mentioned pressure roll.

6. In a machine for making corrugated paper board, the combination with a pair of intermeshing paper-corrugating rolls having their rotary axes arranged in a common plane, pressure rolls cooperating with one of said paper-corrugating rolls in angularly-spaced planes intersecting each other in the rotary axis of said corrugating roll, and means for applying a liner web to the corrugated web as it passes around the paper-corrugating roll and between it and said pressure rolls, said pressure rolls being adapted to guide and deliver the corrugated web with its attached liner.

40. 7. The process of making corrugated paper board, which process consists in corrugating a web between a pair of intermeshing paper-corrugating rolls, in applying an adhesive to the outwardly-presented tips of the corrugated web while enmeshed with one of said paper-corrugating rolls, in applying a liner web to said outwardly-presented tips of the web, and in pressing said liner web into intimate contact with said corrugated web 45 while said webs are being passed over the corrugating roll between two pressure rolls which alternately operate on teeth in the corrugating roll.

8. The process of making corrugated paper board, which process consists in silicating the tips of a corrugated web enmeshed with a corrugated roll, in applying a liner web to the silicated tips of said corrugated web, and in pressing said webs into intimate contact 55 with each other around a portion of the periphery of said corrugated roll by means of pressure-applying rolls operating in alternation on said corrugated roll at peripherally-spaced points along said portion of corrugated roll periphery.

9. The process of making corrugated paper board, which process consists in applying a liner web to the silicated tips of one face of a corrugated web, in pressing said webs into intimate contact with each other while passing them around an arcuate portion of a corrugated roll, and in alternately applying pressure to said liner and corrugated webs at angularly-spaced points on said corrugated roll.

10. The process of making corrugated paper board, which process consists in passing a corrugated web part-way around a corrugated roll with its corrugations enmeshed with the corrugated roll, in applying an adhesive to the outwardly-presented tips of the corrugated web carried by said roll, in applying a liner web to said outwardly-presented tips of the corrugated web, and in applying a feeding pressure to said liner and corrugated web at peripherally-spaced points on the corrugating roll during a series of time intervals.

11. The process of making corrugated paper board, which process consists in corrugating a web between a pair of intermeshing paper-corrugating rolls, in applying an adhesive to the outwardly-presented tips of the corrugated web while enmeshed with one of said paper-corrugating rolls, and in applying a liner web to said outwardly-presented tips of the corrugated web by means of pressure rolls operating in alternation with each other upon angularly-spaced teeth of the last-mentioned corrugating roll.

12. The process of making corrugated paper board, which process consists in corrugating a web between a pair of intermeshing paper-corrugating rolls, in applying an adhesive to the outwardly-presented tips of the corrugated web while enmeshed with one of said paper-corrugating rolls, in applying a liner web to said outwardly-presented tips of the corrugated web, and in pressing said liner web into intimate contact with said corrugated web while said webs are being passed over the corrugating roll between two pressure rolls which cooperate in alternation with each other with opposed teeth in the corrugating roll for feeding said webs on to and off of said corrugating roll.
